(57) **CLAIM**

The ornamental design for a wheel, as shown and described.

DESCRIPTION

FIG. 1 is a perspective view of a wheel showing our new design;

FIG. 2 is an elevational view thereof; and,

FIG. 3 is a cross-section thereof taken along line 3—3 in FIG. 2.

The broken line showings of the lug nut apertures form no part of the claimed design.

1 Claim, 3 Drawing Sheets

FIG. 1

FIG. 2

FIG. 3
